SWITCH ADJUSTING MECHANISM

Melvin H. Cummings, North Caldwell, N. J., assignor to Curtiss-Wright Corporation, a corporation of Delaware

Application September 30, 1942, Serial No. 460,295

3 Claims. (Cl. 200—52)

My invention relates to adjusting mechanism for switches.

My invention has particular reference to switch operating mechanism comprising an actuating element adjustable in position with respect to an actuating member therefor.

More particularly, my invention relates to operating mechanism for opening a limit switch included in the feather circuit of an airplane propeller, such operating mechanism comprising an actuating element adjustable in position with respect to a cam surface which moves toward said actuating element during energization of said feather circuit.

Various other objects, advantages and features will become apparent from the following detailed description.

My invention resides in the adjustable switch mechanism, features and combinations of the character hereinafter described and claimed.

For an understanding of my invention and for an illustration of one of the forms thereof, reference is to be had to the accompanying drawing, in which:

Figure 1 is an elevational view showing the flanged end of mechanism which is attached to the hub of an airplane propeller;

Fig. 2 is a sectional view, partly in elevation, showing the mechanism of my invention;

Fig. 3 is a transverse sectional view, partly in elevation, showing the mechanism of Fig. 2; and

Figs. 4 and 5 are views corresponding generally with Fig. 3 and showing different positions of the power-receiving element of the switch.

Referring particularly to Figs. 1 and 2, there is shown a flange 1 which is disposed at one end of a housing 2 forming part of the power unit and power gear assembly for controlling the pitch of airplane propellers as manufactured by Curtiss-Wright Corporation. This assembly comprises a tubular power member 3 on which is disposed a circular cam 4 having channel configuration as indicated in Fig. 2. The cam 4 is cut away as indicated at 5, Fig. 1, to provide spaced sloping surfaces 5a and 5b, the latter being utilizable as a cam surface as hereinafter described.

Projecting laterally from the housing 2 is a boss 6 defining an interior chamber into which extends a member 7 provided at one end with a circular channel-shaped section in which is disposed a sealing ring 8 adapted to coact with the adjacent surface of the cam 4.

In accordance with the invention, a screw 9 is mounted for rotatable movement in opposite walls of the boss 6, the arrangement being such

that said screw 9 is swivelled or otherwise suitably mounted so that it is incapable of moving longitudinally during rotational movement thereof. The exterior threads of the screw 9 coact with threads interiorly formed on the hub 10 of an oscillatory member 11 having a depending section 11a adapted to be actuated by the cam surface 5b.

The oscillatory member 11, on the upper surface thereof, supports a member 12 having a fork-shaped upper section 12a coactable with a groove 13a formed peripherally in a member 13 which carries a switch contact member 14, said member 13 being mounted for reciprocatory or sliding movement in suitable manner. The movable switch contact member 14 is coactable with a switch contact member 15 which is fixed to a member 15a secured to the propeller hub, not shown. As shown in Fig. 2, the contacting ends 20 of the switch members 14 and 15 are enclosed by the telescopically arranged sleeves 16 and 17 formed from suitable electricity-insulating material.

In accordance with the invention, the oscillatory member 11 is slidably related to the member 12, the latter, by reason of the clutching engagement between the fork-shaped end 12a thereof and the contact member 13, remaining stationary when said member 11 is moved under the control 25 of the screw 9. Accordingly, responsive to rotation of the screw 9, the member 11 moves in one direction or the other beneath the stationary member 12. Any suitable arrangement may be provided for slidably relating the members 11 and 12 for movement with respect to each other. As herein shown, the member 12 is provided with a T-shaped slot 12b in which is freely received a T-shaped projection 11b of the lever 11. Other equivalent dove-tail arrangements may be used 30 as desired.

As is clearly shown in Figs. 3, 4 and 5, the head 9a of the screw 9 is disposed exteriorly of the boss 6 as well as the housing 2 so as to be readily engageable by a screw driver. Coactable with said head 9a of the screw 9 is a suitable locking member 18 utilized for releasably retaining the screw 9 in a desired adjusted position.

As is well understood by those familiar with the power unit and power gear assembly referred to above, the switch contact members 14 and 15 constitute a limit switch which is included in the motor-operating feather circuit of the airplane propeller controlled by said assembly. In accordance with well understood practice, when the airplane feather circuit is energized under operator

control, the cam surface 5b of the cam 4 moves counter-clockwise, Fig. 1, and eventually coacts with known mechanism for moving the hereinbefore described contact member 14 from right to left, Fig. 2, to open the feather circuit as soon as the aforesaid motor has moved the airplane propeller to its proper feather position.

As regards this cam surface 5b, it has been the practice, either to file away or build up the same, by adding metal thereto, in order to effect small changes in the position which the airplane propeller assumes when in feather position. In order to do this, an extensive dis-assembling operation is necessary with respect to the apparatus of said assembly. Such dis-assembling of the mechanism is a factory operation rather than a field operation although it is in the field, rather than in the factory, that changes in the feather position of the airplane propeller are required.

By my invention, minute variations in the feather position of the airplane propeller may readily be effected in the field or in any other place merely by the act of rotating the screw 9 in one direction or the other, this screw being readily accessible from the exterior of the disclosed housing. Thus, it is the depending section 11a of the oscillatory member 11 with which the aforesaid cam surface 5b coacts and, by properly rotating the screw 9 (the latter, thereafter, being releasably held in the position to which rotated by the locking member 18), said oscillatory member 11 is moved with respect to the member 12 to move said depending section 11a either toward or from said cam surface 5b so as to change in a desired manner the time at which the feather circuit opens, different positions of said depending section 11a being shown in Figs. 4 and 5.

As will be understood, engagement of the cam surface 5b with the depending section 11a of the member 11 causes the latter to rock in a counter-clockwise direction, Fig. 2, this rocking movement of the member 11 causing the switch contact member 14 to move from right to left, Fig. 2, under the control of the member 12 and thereby open the feather circuit referred to above.

It will be understood in view of the foregoing, that the switch adjusting mechanism of my invention is specially useful in the application thereof hereinbefore described. However, the invention is not to be thus limited because, obviously, said mechanism may advantageously be utilized for controlling electrical circuits other than the one herein specifically referred to.

While the invention has been described with

respect to a certain particular preferred example which gives satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. In mechanism of the character described, an actuating member having clutching engagement with a member to be operated, an oscillatory member slidably related to said actuating member, said oscillatory member carrying and serving as the sole support for said actuating member, said oscillatory member comprising an actuatable section, and means for moving said oscillatory member with respect to said actuating member, movement of said oscillatory member as specified changing the position of its actuatable section with respect to an actuating element therefor, said means comprising a screw mounted for rotatable movement only.

2. In mechanism of the character described, an actuating member having clutching engagement with a member to be operated, an oscillatory member slidably related to said actuating member, said oscillatory member comprising an actuatable section, and means for moving said oscillatory member with respect to said actuating member, movement of said oscillatory member as specified changing the position of its actuatable section with respect to an actuating element therefor, said means comprising a screw mounted for rotatable movement only, said oscillatory member carrying said actuating member and said screw carrying said oscillatory member.

3. In combination, cooperative fixed and movable contacts, a switch-actuating cam surface rotatably movable to different positions, means actuated by said cam surface for moving said movable contact from said fixed contact, a housing for said contacts, said cam and said actuated means, said actuated means comprising an oscillatory member, a member carried thereby in slidable relation for actuating said movable contact, and a screw swivelled in said housing, said screw being threaded to said oscillatory member and rotation thereof moving said oscillatory member with respect to said cam surface, said actuating member and said movable contact remaining stationary during the specified movement of said oscillatory member.

MELVIN H. CUMMINGS.
